METHOD OF FORMING TUBULAR STRUCTURES FROM SHEET METAL

James J. Black, Cincinnati, Ohio, assignor to The
Trailer Company of America, Cincinnati, Ohio,
a corporation of Delaware

Application February 1, 1937, Serial No. 123,333

2 Claims. (Cl. 153—22)

This invention relates to the art of forming sheet metal structures and is particularly directed to a new and improved process or method of forming sheet metal posts, or beams, or other tubular structures. These posts, or beams, or tubular structures may be used for a wide variety of purposes. As exemplary, they may form part of the framework of truck and trailer bodies.

It has been the object of the present invention to provide an improved method of forming tubular structures in a more efficient manner than has prevailed heretofore, particularly with respect to the final tube closing operation. It has been the further object to provide an improved method of fabricating tubular structures in which method the number of dies required to form the structure has been reduced to a minimum.

These objects have been accomplished with the result that the tubular structures are formed more efficiently and are more uniform in shape. There has been a material lessening of die costs and the added ability to use the same dies for forming up a multitude of tubular forms. An unlimited variety of cross sectional configurations may be provided through the medium of a very simple set of dies.

Otherwise described, the present invention resides in the method of bending the sheet metal into channels of various forms and angles without the use of mandrels leading up to a final die operation which bends the channel or semi-formed tubular structure into a completed tube in a single pass by the use of dies or pressing means approaching the semi-formed tubular structure from opposite sides and active on one side wall particularly through the open side of the channel. In other words the tubular structure is formed in sections at each side of a bend and is thereafter completed by a pressing action on the bend causing an articulation or hinging action bringing the sections together.

Other objects and further advantages will be more fully apparent from the description of the accompanying drawings, in which:

Figure 1 is a perspective view of a length of sheet metal stock to be formed into a rectangular tube as an example of one form which may be fabricated by the method of this invention.

Figure 2 is a perspective view showing the first step in forming the tube in which two right angle bends are produced between the angle forming dies to form a channel of the sheet metal strip.

Figure 3 is an end view of the completed channel strip.

Figure 4 is a perspective view showing the second step in which the channel is opened by a third temporary bend along the center of its back by means of the same dies.

Figure 5 is an end view of the work, at the completion of the operation of Figure 4.

Figure 6 is a perspective view showing the third step in which the opened channel strip receives two more bends between the angle forming dies completing the forming of the four corners of the tube.

Figure 7 is an end view of the metal strip at the completion of this operation and prior to the removal of the temporary center bend.

Figure 8 is a perspective view showing the closing of the section by removing the center bend by means of a straightening die substituted for the corner forming die for this purpose.

Figure 9 is an end view of the work after this operation.

Figure 10 is a perspective view showing the completion of the tube.

Figure 11 is an end view of the completed tube.

Figure 12 illustrates another sheet metal tubular structure formed by the method of this invention.

Figure 13 is a perspective view showing the completion of the tubular structure of Figure 12 by the straightening of the center bend by means of dies in the same manner as previously disclosed.

Figures 14, 15, 16 and 17, illustrate various other sheet metal sections which may be formed by this method, the views showing the open and closed positions of the structures as previously disclosed.

Referring to the drawings, the blank strip of sheet metal stock, indicated at 10, is of the proper width to form, after being worked, the rectangular tube form 11, shown in Figures 8 and 9. The various sections which may be fabricated by the method of this invention may be of any length required. In the drawings, for convenience, only a partial length is shown.

The initial formation of the sections is accomplished between the angle forming die 12 and stationary die 13. The dies 12 and 13 are mounted in any metal breaking press suitable for this class of work. The die 12, cooperating with the die 13, has a knife-like or relatively sharp edge and the die 13, has a V-slot 14 in its upper face. In performing its bending function, the upper die 12 descends upon the work which has been placed on the upper face of the die 13 across the V-slot 14. The sheet metal is bent across the edge of the die 12, the metal being supported at each side upon the shoulders at the top of the V-slot. The degree of the angle thus formed in the work depends upon the distance the edge of the die 12 descends into the V-slot at the upper surface of the die, which is determined by the operator of the press.

The method of this invention is put to a varied practice and is of particular value in forming sheet metal structural beams and other forms utilized in the fabrication of the framework of truck and trailer bodies. The formation of the

rectangular tube, illustrated in Figures 2 to 9, illustrates the method of this invention.

Referring to Figures 2 and 3 of the drawings illustrating the first step in the method of forming the tube, the upper die is shown completing the second bend in the blank strip of metal to form it into a channel. The lines of bend are so spaced from the edges to provide bent portions 15, 15 of a width to form a side wall of the tube when the portions are bent into the opposed relationship shown in succeeding operations.

The value of the present simplified method of forming sheet metal sections lies in the facility with which a wide variety of hollow angular sections may be formed on a standard die press utilizing but one set of bending dies for the various forms. This method, besides permitting the shaping of closed tubular sections by a series of simple bending operations, also expedites the forming of any combination of angular bends to comprise a particular shape as desired.

The flexibility of this method as to the variety of shapes which may be executed is due to the method through which the various angles are formed by direct bending between dies and elimination of the use of mandrels for defining the desired shape. Since the sections are required to be of considerable length, the use of mandrels would be difficult and expensive.

30 The principle of directly forming the angles of the hollow sections between bending dies without the use of a mandrel to sustain the walls of the hollow section against collapse is predicated upon the practice hereinafter disclosed.

35 After the preliminary operation of forming the blank into the channel form of Figures 2 and 3, it is obvious that it would be impossible to proceed to form the next two angles to complete the rectangle in the same manner, as the angle 40 forming die 12 must work on the inside of the hollow tube through an open side thereof. In order to provide the required open side for the die to enter the section, the channel is now turned upside down and bent centrally as at 16, 45 so as to form a shape somewhat like an M, as shown in Figures 4 and 5 of the drawings, this operation being in this instance, the second step in the method.

This third break 16 is temporary and is subject to removal after the next operation and is the basis of the present invention. It will be noted that the channel is thus opened outwardly, providing sufficient clearance for the entry of the upper die 12 to form the next two necessary 55 angles or corners in the section as shown in Figures 6 and 7. The treatment of the work at this point consists in forming a right angle bend 17 medially of each of the legs of the middle portion of the M. The resulting shape may be 60 described as an angularly disposed pair of U-shapes joined at the temporary break. This operation comprises the third step in the formation of the rectangular section by this method.

Figures 8 and 9 illustrate the fourth operation 65 in the forming of the section. This operation consists in removing the temporary bend or break previously formed and producing a straight side wall 18 which articulation or hinge action results in bringing the U-shapes to an opposed 70 relationship, thus creating the rectangular shape of the section as shown.

As shown in Figure 8, the die 19 is relatively thin, providing however a straight lower edge 19a for engaging the temporary bend. This die 75 passes slightly below the surface of the lower

die 18; that is a little past the point at which it would straighten the wall 18 of the tubular structure. This is done so that the wall will be straight when it springs back a slight amount when released by the dies, which springing occurs normally after the bending of plate material. This brings the adjacent edges of the portions 15, 15, against the sides of the moving die and when the die is withdrawn, these edges tend to spring together to the point where they substantially touch. There remains, however, a relatively narrow slit 20 which is removed as set forth hereinafter.

The resulting beam is now substantially rectangular in cross section and is complete with the exception of the elimination of the slit 20 remaining centrally of the upper side wall which is to be removed in the next operation. It will be noted at this point that the corners 17, 17 previously formed were so located to provide a 20 wall 18 somewhat wider than the opposite parallel wall as formed by the two portions 15, 15, so that the adjacent edges of the two portions do not abut, there being a sufficient amount of clearance therebetween to permit the insertion 25 and removal of the straightening die 19.

The final step in the method of forming the hollow rectangular section is shown in Figures 10 and 11. In this operation the work is disposed between dies 21 and 22 to close the slit 20. The 30 seam 23 thus formed at this abutment is in some instances welded shut in order to strengthen the finished beam.

Several other forms of hollow sections formed by this method are illustrated in Figures 12 to 17 35 of the drawings. These various cross sections are shown to illustrate the variety of configuration which may be formed by the present method. It will be readily understood from these views that the method is applicable to a large variety 40 of shapes and sizes of beams and posts. The forms illustrated have been fabricated by the same method as disclosed in connection with the rectangular tube with the exception of having 45 different combinations and a greater number of right angle bends. Since the method of forming these configurations is identical to that employed in the forming of the rectangular tube, no showing is made of these steps in the drawings. The final steps show the removal of the temporary 50 bend for completing the semi-completed forms.

Having described my invention, I claim:

1. The method of forming a tubular structure comprising the steps of; bending a strip of sheet metal to form a channel, temporarily bending 55 the back wall of the channel by pressure applied at the back side thereof, forming additional bends in the back wall by pressure applied through the open side of the channel for completing the side walls and, thereafter straightening the temporarily formed bend by applying pressure to it through the open side of the channel for substantially closing the tubular structure.

2. The method of forming a tubular structure from an open channel strip of sheet metal consisting of; temporarily bending the channel strip by pressure applied longitudinally of the back thereof for temporarily opening the channel, making the finished bends along the channel by dies, one of which engages the inner side of the 60 channel, and thereafter straightening the temporary bend by pressure applied through the open side of the channel for substantially closing the same.
